WIRE MILL EQUIPMENT

Lafe Young and Alfred A. Boyle, Alton, Ill., assignor to Laclede Steel Company, St. Louis, Mo., a corporation of Missouri

Application December 24, 1937, Serial No. 181,667

5 Claims. (Cl. 214—91)

Our invention relates to wire mill equipment and more particularly to apparatus for facilitating both the forming of the wire into bundles of any desired content and the supplying of wire in relatively large quantities to machines utilizing it. Heretofore it has been the practice in wire mill work to wind the wire as it comes from the drawing dies upon a support known as a stripper-reel. Such reels when filled with wire are difficult to handle by the workmen if they are made to contain a large quantity of wire. It has, therefore, been customary to use reels of relatively small height which will accommodate only such a quantity of wire as can readily be 10 manually manipulated.

It is the principal object of our invention to provide a stripper-reel of relatively great height which will accommodate a relatively large quantity of wire. To accomplish this we provide, for 20 cooperation with said reel, handling mechanism both for the reel itself and for the bundles of wire divided from the contents of the reel. In this way we render feasible the manipulation of large reels to form bundles of wire of any desired 25 size. It will be evident that such large reels will prove superior to the usual size in supplying wire to machines of any kind utilizing such wire for any purpose.

In the accompanying drawings which illustrate 30 one form of wire mill equipment made in accordance with our invention Figure 1 is a vertical central section of a stripper-reel and a portion of a support on which it is carried; Figure 2 is a top plan view of the reel; Figure 3 is an enlarged section taken on the line 3—3 of Figure 1; Figure 4 is a side view of the reel and bundle handling mechanism, a portion of the skid being broken away; Figure 5 is a top plan view of the parts shown in Figure 4, the reel carrier being shown in a different position; Figure 6 is a section taken on the line 6—6 of Figure 4; Figure 7 is a section taken on the line 7—7 of Figure 4, the turntable being shown in a different position; and Figure 8 is an end view of the parts shown in Figure 4.

45 Referring first to Figures 1, 2 and 3, the stripper-reel legs 10, which are preferably four in number, are long in proportion to the diameter of the reel and are slightly tapering to facilitate the discharge of wire in the bundling operation. The upper end of each leg is provided with an inwardly and downwardly turned portion 11 which is welded or otherwise secured to the upper end of a sleeve 12. The lower end of this sleeve 50 is belled as shown at 13 and is connected to the

legs by braces 14. The lower ends of the legs are preferably flattened and are turned outwardly to form feet 15. These feet 15 serve not only to support the reel but also as stops to prevent the coil of wire wound on the reel from slipping off the reel when it is being transferred from one position to another. Extending between two opposite legs near their upper ends is a hook bar 16 for engagement with the hook of a crane or the like to raise and lower the reel.

10 In Figure 1 we have shown the reel carried by a support comprising a pan 17 and spider 18 having an anti-friction bearing 19 interposed between them. Carried by the spider 18 is a spindle 20 the upper end of which is adapted 15 to enter the sleeve 12 and form therewith a guide and bearing for the reel. In the upper end of the spindle is a bushing 21 (Figure 3) between which and a pilot or centering pin 22 is an anti-friction bearing 23. The conical form of this 20 pin together with the belled form of the sleeve 12 facilitates the positioning of the reel upon the support. The spindle is preferably provided with a dust guard 24 to protect the bearing 19.

25 Referring now to Figures 4 to 8, a pair of uprights 25 are carried on a base 26. Pivotally mounted between these uprights on a shaft 27 is a frame 28 carrying a pointed pin 29 adapted to enter the sleeve 12 of the reel in a manner similar to the spindle 20. The pin 29 terminates in a 30 collar 42 adapted to contact with the lower end of the sleeve 12 to support the reel in position on the frame 28. The frame 28 may assume either a vertical position as shown in Figures 4 and 6 or a horizontal position as shown in Figures 5 and 8. It is held in the former position by a stop 30 secured to the front faces of the uprights 25 and in the latter by a stop 31 carried on the upper ends of said uprights. The base 26 is attached to a frame work 32 supporting rails 33 forming the horizontal portion of a skid. The forward ends of these rails are extended downwardly to form the inclined portion 34 of the skid terminating in a bundle rack 35 slightly inclined from the perpendicular so that a bundle of wire 36 may be supported against it in convenient 40 position to be engaged by the hook of a crane passing between the two rails forming the rack. These rails are spaced by an H-shaped brace 45 37 (Figure 8).

50 Situated in the center of the frame work 32 is a post 38 having a pivot 39 on which is mounted a block 40 carrying a pair of short rails 33' adapted to be brought into alignment with the rails 33 to form the horizontal portion of the 55

skid. The block 40 and rails 33' together form a turntable upon which a bundle 36' of wire may be deposited from the reel in the position shown in dotted lines in Figures 4 and 5. The turntable permits the bundle to be rotated in a horizontal plane, that is, around its axis, permitting access to all sides of it so that a workman may not only properly form the bundle but readily apply tie wires 41 to it to hold it in shape.

10 The operation of our wire mill equipment is as follows. The stripper-reel is mounted on a wire drawing block of any usual construction, being set in place before starting to wind the wire on the block. As the wire is drawn, it is forced up from the block onto the reel and this operation is continued until the entire height of the reel is filled with a continuous coil 36 of wire. The reel is now raised from the block by the engagement with the bar 16 of the hook of a crane or other hoisting device; the reel is transferred to position over the uprights 25, the frame 28 being in vertical position; and the reel is then lowered to cause its sleeve 12 to surround pin 29, the lower end of the sleeve resting on collar 42 to support the reel on frame 28. The frame is now swung from vertical to horizontal position to locate the end of the reel over the turntable. Sections of wire of any desired size may now be formed from the continuous coil 36 on the reel 30 by cutting the wire at the desired points. Each section of wire as it is severed from the coil is slid off the reel and deposited upon the turntable where it may be manipulated to bring it into proper form, that is, that of an annulus of circular cross section and secured into a bundle by tie wires 41. The rails 33' first being brought into alignment with the rails 33 to form a continuous skid track, the bundle is now slid down the inclined portion 34 of the skid and turned 35 from its inclined position to a substantially perpendicular position against the rack 35 where it may readily be engaged by the hook of a crane and transferred to any desired place. In case it is not desired to form the wire of the continuous coil on the reel into bundles but to utilize it in a wire working machine it is transferred from the drawing block to the support shown in Figure 1 or some other support permitting rotation of the reel. From such support the 40 entire length of wire on the reel may be fed to the machine without interruption.

Having fully described our invention, what we claim as new and desire to secure by Letters Patent of the United States is:

55 1. In a device of the class described, a detachable stripper-reel, a reel supporting member movable from vertical to horizontal position, and a skid, said skid comprising a horizontal portion

for supporting a coil of wire in horizontal position, an inclined portion, and a bundle rack against which a coil may be upended from the inclined portion, the horizontal portion of said skid being so positioned with relation to the reel 5 supporting member as to receive severed sections of wire from a reel carried on the member when the latter is in horizontal position.

2. In a device of the class described, a detachable stripper-reel, a reel supporting member movable from vertical to horizontal position, and a skid including a turntable for supporting a coil of wire in horizontal position, said turntable being so positioned with relation to the reel supporting member as to receive severed sections of 10 wire from a reel carried on the member when the latter is in horizontal position.

3. In a device of the class described, a detachable stripper-reel, a reel supporting member movable from vertical to horizontal position, 20 and a skid, said skid comprising a horizontal portion for supporting a coil of wire in horizontal position, an inclined portion, and a bundle rack against which a coil may be upended from the inclined portion, the horizontal portion of the 25 skid including a turntable, said turntable being so positioned with relation to the reel supporting member as to receive severed sections of wire from a reel carried on the member when the latter is in horizontal position.

4. In a device of the class described, a pair of uprights, a frame pivoted between said uprights to swing from vertical to horizontal position, a centering pin carried by said frame, a stripper-reel provided with a central sleeve for engagement with said pin, and a skid comprising a pair of rails terminating in an approximately vertical bundle rack, said skid being so located with respect to the frame as to receive severed sections of wire from the reel carried on the frame when 35 the latter is in horizontal position.

5. In a device of the class described, a pair of uprights, a frame pivoted between said uprights to swing from vertical to horizontal position, a centering pin carried by said frame, a stripper-reel provided with a central sleeve for engagement with said pin, a skid comprising a pair of rails terminating in an approximately vertical bundle rack, and a turntable including a pair of rails adapted to be brought into alignment 50 with and form in effect a part of said skid rails, said turntable being so located with respect to the frame as to receive severed sections of wire from the reel carried on the frame when the latter is in horizontal position.

LAFE YOUNG,
ALFRED A. BOYLE.
